ENGINE STARTER

John W. Fitz Gerald, Milwaukee, Wis., assignor to
 Briggs & Stratton Corporation, Milwaukee,
 Wis., a corporation of Delaware

Application June 27, 1941, Serial No. 399,978

2 Claims. (Cl. 74—7)

This invention relates to engine starters of the automatically meshed and demeshed type and has as its purpose the provision of improved means for holding the pinion in its retracted position.

In the operation of starters of this type it is essential to provide some means for holding the pinion against drifting or creeping forwardly into engagement with the ring gear while the engine is in operation. Heretofore, this means has taken various forms some of which have been successful and others not.

One of the faults of many of the past anti-creep devices has been their opposition to traversal of the pinion toward driving position during operation of the starter; and it is therefore an object of this invention to provide an anti-creep device for automatic starters which is rendered inactive or disabled as a consequence to revolution of the power driven portion of the starter in the event it is not immediately released to thereby free the pinion for unhindered and unrestricted traversal toward driving position.

Another consequence of starters of this type especially when used on high-speed engines has been the tendency of the pinion to rebound from its retracted position, and while means have been provided in the past to prevent such rebound, this invention combines the two expedients, namely, means for preventing drifting of the pinion into mesh with the ring gear, and means for preventing rebound.

It is thus a further object of this invention to provide a simple manner of combining these two devices into a single unit and for controlling both of them from the same centrifugally responsive means.

With the above and other objects in view which will appear as the description proceeds, this invention resides in the novel construction, combination and arrangement of parts substantially as hereinafter described, and more particularly defined by the appended claims, it being understood that such changes in the precise embodiment of the hereindisclosed invention may be made as come within the scope of the claims.

The accompanying drawing illustrates two complete examples of the physical embodiment of the invention constructed in accordance with the best modes so far devised for the practical application of the principles thereof, and in which:

Figure 1 is a side view of an engine starter embodying this invention, parts thereof being broken away and shown in section;

Figure 2 is a cross sectional view taken through Figure 1 on the plane of the line 2—2;

Figure 3 is a perspective view of the starter;

Figure 4 is a fragmentary sectional view taken through Figure 2 on the plane of the line 4—4;

Figure 5 is a top view of a portion of the starter to show the application of this invention thereto; and

Figure 6 is an enlarged sectional view similar to Figure 2 but illustrating a slightly modified embodiment of the invention.

Referring now particularly to the accompanying drawing in which like numerals indicate like parts, the numeral 5 designates a starter drive shaft which as is customary is the armature shaft of an electric motor 6.

The starter, designated generally by the numeral 7, is mounted on the shaft and includes a pinion 8 movable to and from a driving position 10 meshed with a ring gear 9 on an engine (not shown) to be started.

The specific construction of the starter forms no part of this invention and hence need not be described in detail. It is sufficient to state that the drive shaft 5 has a power or actuator unit indicated generally by the numeral 10 fixed thereto to revolve with the shaft and that the pinion or starter gear has a cylindrical extension or sleeve 11 internally threaded to receive a screw threaded part 12 of the power or actuator unit.

A rubber collar or ring 13 incorporated in the power or actuator unit provides a resilient driving connection between the shaft 5 and the screw member 12 in the manner well understood by those skilled in the art. The rubber ring or collar is confined between driving and driven flanges 13 and 14 respectively. The latter, which is fixed to the screw member 12 has a pivot post 15 projecting therefrom and medially pivoted on this post is a latch member 16.

The latch member 16 is preferably formed from sheet metal and is substantially in the form of a rectangular box having front and back side walls 17 and 18 medially apertured to receive the pivot post, and end walls 19 and 20.

The end walls 19 and 20 have lugs 19' and 20' projecting therefrom toward the axis of the starter to be engageable in an annular groove 21 in the cylindrical sleeve or extension 11 of the pinion. The tongues 19' and 20' are so positioned with relation to each other and the diameter of the sleeve 11 that only one of them can be engaged in the groove 21 at any given time.

The rear and front edges of the tongue 19' are inclined or rounded so that the tongue can be

cammed out of the groove 21' while the rear or inner edge of the tongue 20' is square, and its outer or front edge is inclined to provide a cam surface 22.

A torsion spring 23 coiled about the pivot post between the side walls of the latch member imposes a clockwise turning moment on the latch member when viewed as in Figure 2 to bias the same to a position at which the tongue 19' engages in the groove 21. In this position the other tongue 20' is of course lifted a substantial distance out of the groove.

Extending out from the end wall 19 of the latch member is a weighted arm 24 which provides centrifugally responsive means operable in opposition to the bias of the spring 23 when the starter is spinning to hold the tongue 19' out of the groove 21 and hold the tongue 20' in position to cam itself into the groove upon retraction of the pinion.

By virtue of the square inner edge of the tongue 20' its engagement in the groove 21 effectively prevents rebound of the pinion, while engagement of the tongue 19' in the groove 21 serves as an anti-drift or anti-creep device to prevent the pinion from creeping forwardly into engagement with the ring gear when the starter is not in operation but the engine is running.

If, when the starter begins to operate, the tongue or detent 19' does not immediately cam out of the groove, centrifugal force acting on the weight 24 will lift the same out of the groove 11 and free the pinion for traversal toward its driving position.

By virtue of the balance of forces between the spring 23 and the centrifugal force acting on the weight 24 the tongue 20' cannot engage in the groove before the pinion begins its traversal toward driving position, and the instant such forward advance of the pinion starts, the square shoulder on the rear of the tongue 20' prevents engagement of the tongue in the groove.

However, as noted hereinbefore when the starter is spinning at the speed it reaches during the starting operation, the weight 24 throws the latch member to the position at which its tongue 20' lies in the path of the end of the sleeve 11 so that upon retraction of the pinion when the engine starts, the cam surface 22 on the front edge of the tongue 20' cams the latch up over the end of the sleeve to enable engagement of the tongue 20' in the groove.

Such engagement prevents the objectionable rebound and obtains until the speed of the starter rotation decreases sufficiently to allow the spring 23 to overcome the centrifugal force acting on the latch whereupon the tongue 19' is engaged in the groove as noted hereinbefore.

In the embodiment of the invention shown in Figure 6 the rebound prevention feature of the invention is omitted, but in all other respects the device operates in the manner described. To this end the latching member is pivoted at one end and has but one detent or tongue 25 at its free end to be yieldingly urged into the groove 21 by the torsion spring and to be lifted out of the groove by the weight 24 responding to centrifugal force as the starter begins to spin.

From the foregoing description taken in connection with the accompanying drawing, it will be readily apparent that this invention provides an improved manner of guarding against drifting or creeping of the pinion toward driving position and that it provides a simple manner

of incorporating this function with that of an anti-rebound device.

What I claim as my invention is:

1. In an engine starter: a drive shaft; a driving member movable along the shaft to and from an operative driving position engaging a member of an engine to be started; an internally screw threaded sleeve having one end joined to the driving member and having an annular shoulder adjacent to but spaced inwardly of its opposite end; actuating means drivingly connected with the shaft to rotate therewith and having a screw threaded connection with said sleeve for effecting traversal of the driving member toward operative driving position during initial operation of the starter and for retracting the driving member to an inoperative retracted position upon starting of the engine; a latch member medially pivoted on said actuating means to rotate therewith, said latch member having latch parts at opposite sides of its pivot engageable behind said shoulder on the sleeve in the retracted position of the driving member to oppose traversal of the driving member toward operative position, said parts being so disposed with relation to each other and the shoulder on the sleeve that only one of said parts can be engaged behind said shoulder at any given time; spring means biasing the latch member to a position at which one of its latch parts engages behind the shoulder to prevent creeping of the driving member toward its operative driving position; centrifugally responsive means on the actuating means connected with the latch member operable in response to centrifugal force during operation of the starter to overcome said spring means and swing the latch member in a direction to disengage said first-designated latch part thereof from the shoulder to thereby free the driving member for traversal to its operative position, such traversal of the driving member to its operative position causing said opposite end of the sleeve to pass outwardly away from the latch member, said centrifugally responsive means maintaining the other of said latch parts in a potentially operative latching position in the path of said opposite end of the sleeve during cranking of the engine and retraction of the driving member to its inoperative retracted position; and cooperating cam surfaces on the second-designated latch part and said opposite end of the sleeve engageable upon retraction of the driving member to lift said second-designated latch part against the action of the centrifugally responsive means and allow passage of said opposite end of the sleeve thereunder for latching engagement of the second-designated latch part with said shoulder to prevent rebounding of the drive member.
2. In an engine starter: a drive shaft; a driving member movable along the shaft to and from an operative driving position engaging a member of an engine to be started; an internally screw threaded sleeve having one end drivingly connected to the driving member and having an annular groove in its periphery adjacent to but spaced inwardly of its opposite end; actuating means drivingly connected with the shaft to rotate therewith and having a screw threaded connection with said sleeve for effecting traversal of the driving member to an operative driving position upon initial operation of the starter, and for retracting the driving member to an inoperative retracted position upon starting of the engine; a centrifugally responsive latch

member medially pivoted on said actuating means to rotate therewith and having latch parts at opposite sides of its pivot in line with the groove in said sleeve in the retracted position of the driving member, centrifugal force acting on the latch member during operation of the starter yieldably maintaining one of said latch parts disposed in the path of said opposite end of the sleeve; cooperating cam surfaces on said latch part and said opposite end of the sleeve engageable upon retraction of the driving member following starting of the engine to effect lifting of said latch part out of the path of the

10 sleeve to thereby enable engagement of said latch part in the annular groove in the sleeve so as to prevent rebounding of the driving member after its retraction; and a spring biasing the latch member to a position disengaging said latch part thereof from the groove and engaging the other of said latch parts in said groove upon cessation of the effect of centrifugal force on the latch member to hold the driving member against creeping toward operative position while the starter is at rest.

JOHN W. FITZ GERALD.
